E. WYKES

OIL BURNING STOCK TANK HEATER

Filed April 16, 1924

Patented Nov. 6, 1928.

1,690,659

UNITED STATES PATENT OFFICE.

ERNEST WYKES, OF HUMBOLDT, IOWA.

OIL-BURNING STOCK-TANK HEATER.

Application filed April 16, 1924. Serial No. 706,934.

An object of this invention is to provide an improved construction for oil-burning stock-tank heaters.

A further object of this invention is to provide an improved construction of means for supplying air to a stock-tank heater.

A further object of this invention is to provide improved means for supporting a fuel tank and distributing the contents thereof to 10 a burner.

A further object of this invention is to provide an improved construction for a radiator in a stock-tank heater.

My invention consists in the construction, 15 arrangement, and combination of elements, hereinafter set forth, pointed out in the claims and illustrated by the accompanying drawing, in which—

Figure 1 is a side elevation, partly in section, of the complete device. Figure 2 is a plan view of the device shown in Figure 1, dotted lines indicating interior parts.

In the construction of the device as shown the numeral 1 designates a burner chamber which may be made of separate plates connected and sealed together. The burner chamber 1 preferably is prismatic in form and of a height substantially double its width and is adapted to be mounted in a stock-tank and 25 partially submerged therein. An oil-burner 3 is removably and replaceably mounted within and rests on the bottom of the chamber 1 and the major portion of the bottom of said burner preferably is spaced from the bottom 30 of the chamber to avoid excessive cooling of the burner on account of the proximity of cold water surrounding said chamber. The burner 3 is formed with an upwardly-opening cavity, having a ridged or serrated bottom adapted to contain liquid fuel, such as kerosene or distillate. An air conduit 4 is mounted in the chamber 1 and the body thereof may be formed open on one side toward 35 an adjacent wall of the chamber and formed with flanges 4' adapted to be bolted to said wall. The conduit 4 extends above and laterally across the adjacent wall of the chamber 1 and is provided with a downwardly-opening mouth 5 outside said wall. The lower end 40 portion of the conduit 4 is extended laterally and downwardly on curves toward, and terminates with an open end slightly above the burner 3. A fuel tank 6 is mounted on and fixed to the upper end portion of the conduit 4 and a fuel pipe 7, controlled by a needle-valve 8, leads from said tank through the in-

wardly-extending end portion of the conduit 4 and terminates with an open lower end axially of the lower open end of the conduit and of the burner 3. The fuel pipe 7 extends, 60 in part, vertically through the central portion of the chamber 1, and a cover 11 is formed of two parts slidably mounted in opposite directions of said pipe and adapted to close the upper end of said chamber. A window 65 9, preferably made of mica, is mounted in one part of the cover 11. A chamber 2 preferably constructed of metal by molding, substantially circular in cross-section, is formed with a flange 2' adapted to be bolted to one wall of 70 the chamber 1, said chamber 2 being formed with an open end communicating with hole 1' in said wall of the chamber 1. The chamber 2 also is formed with a foot 2'' adapted to rest on the floor of a tank. The end portion of the 75 chamber 2 adjacent the chamber 1 is oblique in order that when the chambers are connected the bottom of the chamber 2 will be inclined toward the chamber 1. Thus provision is made for draining condensation from the chamber 2 into the chamber 1 and also for upward draft through the hole 1'. The chamber 2 is tapered throughout its length and is recurved substantially at its center, the upper portion of the chamber 80 trending at an acute angle to the lower portion thereof and terminating in a circular vertical upper end adapted to receive a flue 10. The chamber 2 has its upper end substantially flush with the top of the chamber 1 and above 85 the level of the water in the tank, and the flue 10 may extend any desired distance upwardly to give draft for oil combustion in said chamber 1.

In practical use, a quantity of liquid fuel 90 is deposited through the pipe 7 on the burner 3. The liquid fuel on the burner may be ignited by means introduced through the top of the chamber 1 when one or the other part 11 of the cover is moved outwardly. A further and continuous supply of liquid fuel is 95 led to the burner 3 through the pipe 7 and is regulated and controlled by manual adjustment of the needle valve 8. A supply of atmospheric air to maintain combustion on the 100 burner 3 is provided through the conduit 4 and the entrance to said conduit opens downwardly to guard against the introduction of rain, sleet or snow to the chamber 1. When the cover 11 is closed the products of combustion 105 pass away from the chamber 1 through the hole 1', chamber 2 and flue 10 and heat 110

said chamber 2. The chamber 2 being tapered has a tendency to retain the heating medium therein and the curved form of said chamber also has the same tendency. Heat 5 is radiated from the chamber 2 and raises the temperature of the water in which the heater is submerged partially. The curved form of the chamber 2 also contributes to compact assembly of the devices and renders the location 10 of the heater in the tank more stable. The burner 3 may be removed, cleaned and replaced or substituted by another as desired. Whenever liquid fuel may not be available, the burner 3 and pipe 7 may be removed and 15 other fuel may be employed and burned in the chamber 1.

I claim as my invention—

1. In an oil-burning stock tank heater, the combination with a combustion chamber having an open upper end and a radiator recurved between its ends and having one end communicating with said combustion chamber, of a burner loosely mounted within said combustion chamber, a removable cover on 20 the open end of said chamber, an air conduit hooked over one wall of said chamber with its upper end outside of and downwardly opening relative to said chamber, said conduit passing through said cover and having

its lower end opening above and spaced from 30 said burner, a fuel tank carried by the upper end of said conduit and a valve-controlled fuel pipe leading from said tank through said cover and having its lower end intersecting said conduit to discharge axially above said 35 burner.

2. In an oil-burning stock tank heater, the combination with a combustion chamber having an open upper end, a burner loosely mounted therein, a removable cover on the 40 open end of said combustion chamber and a recurved radiator secured to and communicating with said chamber adjacent the bottom thereof, of an air and fuel supply unit comprising an air conduit hooked over one wall 45 of said chamber with its upper end outside of and downwardly opening relative to said chamber, said conduit passing through said cover and having its lower end above, spaced from and opening toward said burner, a fuel 50 tank carried by the upper end of said conduit, a valve-controlled fuel pipe leading from said tank through said cover and having its lower end intersecting said conduit to discharge 55 axially thereof above and on said burner. 55

In testimony whereof I affix my signature.

ERNEST WYKES.
